HARVEY W. REAUME, OF BROADHEAD, COLORADO.

SHIELDING APPLIANCE FOR MINE TROLLEY-WIRES.

1,243,220.

Specification of Letters Patent. Patented Oct. 16, 1917.

Application filed September 21, 1916. Serial No. 121,474.

To all whom it may concern:

Be it known that I, HARVEY W. REAUME, a citizen of the United States, residing at Broadhead, in the county of Las Animas and 5 State of Colorado, have invented certain new and useful Improvements in Shielding Appliances for Mine Trolley-Wires, of which the following is a specification.

My invention relates to trolley-wire shields 10 for use in mines in which the ore or coal is conveyed by means of electrically operated railways.

In order to prevent accidents by contact 15 with the exposed trolley-wires suspended from the roofs of mine-tunnels, it is customary to shield the wires by means of boards or other protective devices fastened to the mine-roofs by any suitable means. In Colorado and other mining States, shielding of 20 the trolley wires is made compulsory by law and it is therefore of considerable importance that means are provided to effect this result in a simple and satisfactory manner.

The most common method of shielding the 25 wires, heretofore employed, is to drill holes in the mine-roof, plug these holes with wood and then nail boards to the projecting ends of the plugs at opposite sides of the wires.

It is obvious that principally by reason of 30 the irregular formation of mine roofs, and the fragile nature of the plugs, this method of shielding is unreliable and otherwise unsatisfactory, and it is the principal object of 35 the present invention to provide a simple appliance by which shields may be securely suspended from the hangers used to fasten the trolley wires to the mine-roofs.

Another object of my invention is to provide 40 means for the suspension of the shields so that they may be readily moved to afford access to the wire or the hangers for repairs or adjustment.

I attain these objects by the provision of 45 hoods which are adapted for attachment to the hangers by means of which the trolley wires are suspended from the mine roofs, and shields which are hinged to the hoods and which normally hang perpendicularly 50 at opposite sides of the wires.

An embodiment of my invention is shown in the accompanying drawings in the various views of which like parts are similarly designated, and in which—

55 Figure 1 represents a longitudinal section through the roof of a mine-tunnel showing

my improved shielding-appliance in its operative position with relation to a trolley-wire suspended from the roof,

Fig. 2, an enlarged section along the line 60 2—2, Fig. 1, and

Fig. 3, a section taken on the line 3—3, Fig. 2.

Referring to the drawings, the reference 65 numeral 2 designates the roof of a mine-tunnel, and 3 the trolley-wire suspended therefrom by means of hangers 4.

In the drawings I have shown my improved shields in connection with hangers of a type commonly used in present mine-railway construction, but I desire it understood that my invention is independent of any particular form of hanger and may be used effectively in connection with any of the many trolley-wire hangers at present on 75 the market.

The hangers shown in the drawings are composed of a stem 5 having at its upper end a longitudinally split socket 6 for its rigid connection with a wooden-plug 7 driven into 80 an opening in the roof of the mine tunnel.

The stem has at its lower end, a threaded stud 8 of reduced diameter, for the attachment of a bell 19 which at its lower end carries the clamp 20 in which the trolley wire is 85 secured.

My improved shielding-appliance comprises a hood 9 made of sheet metal and bent to form two divergent side-members 10 and a cross-member 12 connecting the upper 90 edges thereof.

The cross-member 12 has an opening for the reception of the stud 8 at the lower end of the stem 5 and the side members 10 are bent at their lower edges to provide hinge- 95 knuckles 13.

Hinge-blades 14 provided with knuckles corresponding with those on the opposite edges of the hood are suspended therefrom by means of pins 15, there being two blades 100 at each side of the hood for the attachment of the ends of the sections 16 of shields made of wood or other suitable material.

The shield-sections are attached to the hinge-blades by means of counter-sunk 105 screws and hang, in practice, perpendicularly from the edges of the hood, it being desirable to construct their hinge-connections so as to prevent or limit their inward motion.

By arranging the shield sections in longitudinal alinement and end-to-end contiguous

ity, the trolley-wires extending between the shields are adequately protected from contact with other objects, it being understood that the hinged connections of the shield-
5 sections with the hoods permit of their being lifted to afford access to the wire or the hangers for purposes of adjustment or repairs.

The hoods 10 suspended from the bells 10 which are attached to the screw studs at the lower ends of the stems 4, present a stable medium for the suspensions of the shields 16, and nuts 17 screwed on the studs against the upper surfaces of the cross-members 12 15 of the hood, are applied to securely fasten the hoods against accidental displacement.

Having thus described my improved shielding appliance in a form designed for use in connection with hangers of the specific construction shown in the drawings, I desire it understood that modifications in the construction and arrangement of its parts, to adapt it for its attachment to hangers of different design, may be resorted to 25 within the spirit of my invention as defined in the following claims:

1. In a shielding appliance for mine-trolley wires, a hood including downwardly diverging side-members having at their 30 lower ends, means for the attachment of

shields, and a cross-member connecting the upper ends of said side-members and having an opening for the attachment of the hood to a hanger by which a trolley-wire is suspended from a mine-roof.

35

2. In a shielding appliance for mine-trolley wires, a hood including downwardly diverging side-members, and a cross-member connecting the upper ends of said side-members and having an opening for the attachment of the hood to a hanger by which a trolley-wire is suspended from a mine-roof, and hinge-blades pivotally suspended from the lower ends of said side-members.

40

3. In a shielding appliance for mine-trolley wires, a hood including downwardly diverging side-members, and a cross-member connecting the upper ends of said side-members and having an opening for the attachment of the hood to a hanger by which a trolley-wire is suspended from a mine-roof, and hinge-blades pivotally suspended in pairs from the lower ends of said side-members.

45

In testimony whereof I have affixed my 55 signature in presence of two witnesses.

HARVEY W. REAUME.
